UNITED STATES PATENT OFFICE.

FREDERICK S. PINKUS, OF NEW YORK, N. Y.

DESIGN FOR A TABLE-CLOTH, &c.

SPECIFICATION forming part of Design No. 20,101, dated August 12, 1890.

Application filed July 21, 1890. Serial No. 359,445. Term of patent 7 years.

To all whom it may concern:

Be it known that I, FREDERICK S. PINKUS, a citizen of the United States, residing in the city, county, and State of New York, have invented and produced a new and original Design for Table-Cloths, &c., of which the following is a specification.

In the accompanying drawing the figure represents a plan view of my design.

My design comprises the representation of a car-wheel in the center with wings extending from either side, the car-wheel being shown in perspective, while in each of the inside corners a car-wheel is represented in side elevation with the folded wings extending therefrom. These are inclosed by an ornamental border of conventional form, as shown at *a*, and around this border extends a second

border representing clusters of leaves, and outside of this border is a third border composed of parallel lines extending at angles to each other. The outer border *b* is provided with conventional characters inclosing the whole.

What I claim is—

The design herein shown and described, the same comprising a central illustration of the car-wheel and wings with the car-wheels and wings in the corners, these being surrounded by an ornamental border.

In testimony whereof I affix my signature in presence of two witnesses.

FREDERICK S. PINKUS.
